UNITED STATES PATENT OFFICE.

THOMAS B. ATTERBURY, OF PITTSBURG, PENNSYLVANIA.

DESIGN FOR A BOTTLE OR JAR.

SPECIFICATION forming part of Design No. 18,220, dated April 3, 1888.

Application filed February 27, 1888. Serial No. 265,517. Term of patent 7 years.

To all whom it may concern:

Be it known that I, THOMAS B. ATTERBURY, a citizen of the United States, residing at Pittsburg, in the county of Allegheny and State of Pennsylvania, have invented and produced a new and original Design for Bottles or Jars; and I do declare the following to be a full, clear, and exact description of the same, reference being had to the accompanying drawings, forming a part thereof.

My invention relates to designs for glass bottles or jars; and it consists of a body portion larger at the top than at the bottom, and the neck of which has a series of grooves and annular rings.

My invention consists, further, of an ornamental cap or cover for the mouth of the bottle or jar.

Figure 1 is a side view of my newly-designed bottle or jar. Fig. 2 is an edge view. Fig. 3 is a bottom view of the same.

A indicates the main body of the jar, and is larger at the top than at the bottom. The lower portion of the jar below the bulged or swelled portion is oval or elliptical in cross-section, while the upper or bulged portion is round, or nearly so, and terminates at the neck of the jar in an annular ring, B.

C and D are grooves in the neck of the jar, which form the rings or projections E and F. 30 The neck of the jar above the ring F is smaller than the lower portion of the neck. The sides of the cover G are plain. The upper or top portion is oval or convex, as shown at K, and terminates at the edge in an annular 35 groove or depression, L, which gives to the cover a finished or ornamental appearance.

I claim as my invention—

1. The design for bottles or jars, composed of the body A, larger at the top than at the 40 bottom, the lower portion being elliptical in cross-section, the neck of the jar being provided with a series of annular grooves and rings, substantially as shown and described.

2. In the design for a bottle or jar, the cover 45 having an imperforate top oval or convex, and a groove or depression, L, around the edge of the oval, substantially as described and shown.

In testimony whereof I affix my signature in presence of two witnesses.

THOMAS B. ATTERBURY.
